UNITED STATES PATENT OFFICE.

BERT ANDERSON, OF HOUSTON, TEXAS, ASSIGNOR TO ANDERSON, CLAYTON & COMPANY, OF HOUSTON, TEXAS.

BALE TIE.

Application filed February 18, 1928. Serial No. 255,417.

This invention relates to improvements in bale ties and more particularly to an improvement on the bale tie disclosed in my Patent 1,606,331 issued November 9, 1926.

5 The bale tie of my prior patent has its overlapping and underlapping ends struck up to provide a slot and a spanning loop at the overlapping end of the tie, and a corresponding slot and a locking button corresponding 60 to the loop, at the underlapping end of the tie, the said loop and button, in each instance, being provided with a substantially circular enlargement or head, and the button upon the underlapping end of the tie being inserted 65 10 through the slot in the overlapping end and beneath the loop which spans said slot, at the time the tie is applied about the bale and while the bale is under pressure. In actual use I have found that while this construction 70 15 presents a secure locking means for the ends of the tie, the curvilinear edges of the enlargement or head of the button upon the underlapping end of the tie have a tendency to cut through the end of the loop of the over- 75 20 lapping end of the tie, upon expansion of the bale and during handling thereof, after the delivery of the bale from the press. Therefore the present invention has as its primary 80 25 object to provide a bale tie similar to the patented tie but so constructed that, instead of a 85 30 tendency to cut through the end of the loop of the overlapping end, the button of the underlapping end will present squared edges or shoulders and thus insure against tearing or 90 35 ripping of the end of the loop of the overlapping end and thus overcome the disadvantage noted above.

40 While the accompanying drawings and the description which is to follow constitute a disclosure of the preferred embodiment of the invention, it will be understood that various changes may be made within the scope of what is claimed.

In the accompanying drawings:

45 Figure 1 is a plan view of the end of a bale tie embodying the invention looking at the inner side of the tie, the ends being overlapped and interlocked but the tie being in the condition which it will assume when applied about the bale and when not subjected to an expanding stress such as that to which it is subjected when the bale is delivered from the press;

50 Figure 2 is a view similar to Figure 1 looking at the outer side of the connected ends of the tie;

Figure 3 is a view partly in side elevation and partly in longitudinal section illustrating the connected ends of the tie in the condition above described in connection with Figure 1;

60 Figure 4 is a fragmentary perspective view of the overlapping end of the tie;

Figure 5 is a similar view of the underlapping end of the tie;

65 Figure 6 is a detail vertical longitudinal sectional view through portions of the overlapping ends of the tie and illustrating the positions assumed by these ends and the locking elements constituting a part thereof, when the tie is subjected to expansive strain 70 upon removal of the bale from the press.

75 In the drawings the overlapping and underlapping ends of the bale tie are indicated respectively by the numerals 1 and 2 and, as illustrated, the overlapping end 1 is formed 80 with a longitudinal series of loop members 3 which are struck up from the said end of the tie or otherwise formed, and each loop member is of uniform width throughout its length except at its intermediate portion 85 where it is formed with a head 4 defined by lateral extensions of the opposite edges of the loop, the head being preferably located nearer that end of the loop which is the more remote from the extremity of this end of the tie and the said head being of rectangular 90 form as best illustrated in Figures 2 and 4 of the drawings. It will be evident by reference to Figures 1, 3 and 4 of the drawings that the formation of each loop 3 results in the formation of a longitudinal slot 5 in the said overlapping end of the tie, the slot having a widened intermediate portion 6 resulting from the stamping out of the head 4. It will also be observed by reference to Figures 95 3, 4 and 6 of the drawings that the ends of the loop 3 are inclined downwardly in opposite directions at their juncture with the body of the tie, so that each loop has end portions indicated by the numeral 7 uniting the ends to the body of the tie.

100 The underlapping end 2 of the tie is stamped or otherwise formed to provide a plurality of locking buttons indicated by the numeral 8 and each having substantially the same form as the loops 3 of the overlapping end 1 of the tie, each of the buttons being of a length somewhat less than the length of the loops 3 and being provided intermediate its ends with lateral enlargements 9 which 110

are of a rectangular form and which provide a head having straight shoulders 10 at one end extending at right angles to the respective side edges of the button, the ends of the 5 button being integrally connected with the said underlapping end 2, from which they are formed, by connecting portions 11 which are inclined substantially at the same angle as are the connecting portions 7 of the loops 3.

10 The tie is of course made of strap metal, and in the use of the tie it is arranged about the bale while the bale is under compression and the overlapping and underlapping ends of the tie are brought together in overlapped 15 relation and one or more of the buttons 8 of the underlapping end of the tie is engaged in one or several of the slots 5 in the overlapping end 1 of the tie, as the case may be, the heads formed by the lateral projections 9 20 upon the buttons 8, being engaged upwardly through the widened portions 6 of the respective slots 5 in the said overlapping end 1 of the tie, and the overlapped ends of the tie being then permitted to slip longitudinally 25 past each other, at the time the tie and bale are relieved of pressure. This relative slip- page of the overlapped ends of the tie will of course result in the head of the button or buttons, which are in engagement with the 30 slots and loops of the overlapped end of the tie, sliding out of registration with the widened or enlarged portions 6 of the slots 5 and into engagement at their projecting portions 9, over the edges of the overlapping end of 35 the tie at opposite sides of the slot 5 and between the widened portion 6 of the slot and that one of the connecting portions 7 of the respective loop or loops which is located nearer the extremity of this portion of the tie. 40 At this time the buttons and loops which are interlocked will assume approximately the relative positions shown in Figures 1, 2 and 3 of the drawings, but inasmuch as the bale, about which the tie has been arranged, 45 will continue to expand after it has been delivered from the press, the ties which are disposed about the bale will of course be subjected to a considerable degree of expanding strain with the result that the overlapped 50 ends of each tie will tend to further move toward a position of separation and, as a result, the shoulders 10 of the head of the engaged button or buttons of the underlapping end of the tie will be caused to eventual- 55 ly assume substantially the position shown in Figure 6, in which position these shoulders will substantially engage against the connecting portion 7 of the respective loop

with which the button is interlocked, it being understood of course that the loops are 60 of slightly greater width than the buttons, and this engagement of the parts serves of course to prevent any further relative displacement of the overlapped ends of the tie. It will be evident at this point that by providing a head 9 upon each of the buttons 8, of the contour illustrated in the drawings, a decided advantage is gained over the construction illustrated in my prior patent inasmuch as, in the prior patent, the head of each button is of circular marginal form and there is an absence of the well defined shoulders 10 of the present invention and a consequent tendency for the rounded edges of the heads of the buttons of the patented structure to 75 tear through the connecting portion of the respective loop, and which portion corresponds to the portion 7 of the loop of the present invention, whereas, in the present invention, the square shoulders 10 of the head 80 9 of the button do not in any way tend to cut through this connecting portion.

Having thus described the invention, what I claim is:

1. A bale tie including overlapping and underlapping ends, the overlapping end having a struck out loop extending longitudinally thereof and providing a longitudinal slot, the said loop and slot having lateral extensions, the underlapping end of the tie having a struck out button provided with an intermediate rectangular head providing abrupt shoulders at opposite sides of the button, the said button being engaged through the slot in the overlapping end of the tie with 95 the shoulders thereof presented in proximity to one end of the loop.

2. A bale tie including overlapping and underlapping ends, the overlapping end having a struck out loop extending longitudinally thereof and providing a longitudinal slot, the said loop and slot having lateral extensions intermediate their ends and the loop being connected with the said end of the tie by inclined terminal connecting portions, the underlapping end of the tie having a struck out button provided with lateral extensions defining a rectangular head having abrupt shoulders at opposite sides of the button, the said button being engaged through the slot in the overlapping end of the tie with the shoulders thereof presented in proximity to one of the connecting end portions of the loop.

In testimony whereof I affix my signature.
BERT ANDERSON.
